BOTTLE CRATE

Lloyd Hale, Minneapolis, Minn., assignor to G. H. Tennant Company, Minneapolis, Minn., a corporation of Minnesota

Application March 19, 1931, Serial No. 523,711

6 Claims. (Cl. 217—19)

Crates have been constructed for milk bottles and the like, heretofore, wherein a certain construction or type of construction has been followed of a nature to provide partitions to hold the bottles separated one from the other and to permit the same to be handled easily when the bottles are full or empty. When the crate is used as a milk bottle carrier and support the bottles are received in upright position when they are full of milk and permit the milkman to handle the crates filled with these bottles easily. When the bottles are empty they may be inverted and passed through a washing means which thoroughly cleanses and sterilizes the bottles. This is done in the creamery or at the milk station where the bottles are filled.

I have designed a bottle crate which is very adaptable to use as a milk crate and wherein a construction of a different nature is provided. This crate is formed with side walls made up of a series of superimposed slats which are held together at the corners by corner members made of metal or other suitable reinforcing means, the inner corner members having stacking lugs so that one bottle crate may be stacked upon the other. The lower slats on all sides are reinforced by a metal rail to protect the lower edge of the crate.

I have designed a particular form of partition means to form separate compartments for each bottle within the crate and I accomplish this by a metal stamping wherein a series of openings are formed, and these partitions are arranged in relation to the slats which form the side walls so as to hold the partitions in proper position.

It is also a feature of the invention to provide a bottom member formed of a stamping which is provided with recesses for receiving either end of a milk bottle or the like. The bottom is also formed with drain openings in the center of each recess so that the bottles may be inverted and the neck of the bottle will fit into the recess in the bottom to hold the bottle in position so that water and steam may be forced into the same to thoroughly cleanse and sterilize it. The bottom is also designed to be held by or between the edges of the slats so that the crate has a peculiar construction of its own design and formation which departs from the ordinary construction of crates of this character made heretofore.

A feature resides in providing partitions and a bottom portion which is in the form of a sheet-like member having the openings for receiving

the bottles formed therein and the edges of the partitions being formed with a means which may be inserted in a slot formed in the slats which provide the sides of the crate or which may be extended in the crack between two of the superimposed slats. A portion of the partition and bottom may be formed with barbs which project in a manner to form anchoring means for anchoring the edges of the partition locked in the side walls of the crate.

Further, I provide a rivet-like stay-bar which extends to join and connect together the partitions and bottom in a simple and effective manner.

These features, together with the particular details will be more clearly defined in the specification and claims.

In the drawings:

Figure 1 illustrates a perspective view of my crate as it would appear in use.

Figure 2 is a plan view of the same.

Figure 3 is a side sectional view of the crate.

Figure 4 is an enlarged detail of a portion of the crate, showing in dotted lines the manner in which either the neck of the bottle or the base thereof may fit into the recesses formed in the bottom of the crate.

Figure 5 illustrates an enlarged detail of one form of construction of the crate.

Figure 6 illustrates an enlarged sectional detail of a form of construction of the crate.

Figure 7 illustrates another sectional detail of a form of the crate construction.

Figure 8 is a sectional detail of a form of construction of the crate.

Figure 9 illustrates the rivet stay-bolt used in my crate.

Figure 10 is a perspective detail of a portion of the construction illustrated in Figure 7.

Figure 11 is a perspective detail of a portion of the construction illustrated in Figure 8.

The drawings illustrate the bottle crate A which is of a rectangular nature and which is formed with side walls 10 and end walls 11. These walls are made up of a series of wooden slats 12 which are rest edge to edge, one against the other as illustrated in Figure 3.

Inside metal angle corner members 13 are provided with stacking lugs 14 formed on the upper end of the same, while outside corner members 15 of metal are secured over the corners of the crate A and these angle members 13 and 15 may be connected together by rivets extending through the ends of the slats 12. This provides a reinforced corner for the crate A and holds the

slats 12 in rigid position, resting edge to edge, one against the other. The bottom slats 12 on all sides are preferably provided with a channel-shaped reinforcing metal guard rail 16 which protects the bottom edge of the crate A against undue wear in its use over gravity carriers and in sliding the crate along cement floors, as it is used in milk stations. I provide the crate A with sheet metal partitions B which are formed with a series of bottle openings 17. The openings 17 may be formed with depending flanges 18 which tend to reinforce the partitions B as well as providing a band-like flat surface for engagement with the body of the bottles such as C. This construction permits the partitions B to be made of thin sheet metal and the flanges 17 sufficiently reinforce the same so as to give the desired rigidity to the partition, yet permit the same to be made of light weight material, and the flanges form a sufficient resilient engagement for the bottles C so as to guard against breaking.

The outer edge 19 of the partition B may be anchored in a saw-cut, such as 20, formed in the slats 12 so as to support the partition B in the proper spaced relation within the crate A, as illustrated in Figure 5.

These partitions may also be held by a suitable shoulder 21 formed on the side of the slats 12 with the edge 19 anchored in the saw-cut 20. The shoulder 21 is designed to assist in supporting the edges of the partition B in proper position within the crate A.

A further supporting of the edge of the partition B may be accomplished by the construction illustrated in Figures 7 and 10, where I show the edge of the partition cut at 22 in a manner to provide a bent-up lug 23. The edge 19 may then be anchored either in a saw-cut in the slats or between the abutting edges of two of the slats 12 like as illustrated in Figure 7, where the shoulder lug 23 spaces the partition B in relation to the slats 12.

Still another form of holding the edges 19 of the partitions B is exemplified in Figures 8 and 11 and this may be termed the preferred form of holding the edges 10 of the partitions B in position in relation to the slats 12. In this construction the edge 19 is cut at 24 to form the anchoring barbs 25 which are bent to extend in opposite directions to each other and which are formed with a sharp piercing point on the projecting ends. In this form the partition B is set in the crate with the barbs 25 engaging the adjacent edges of the slats 12, then by squeezing or pounding the slats down, the barbs 25 will anchor themselves into the body of each of the adjoining slats and thus hold the edges of the partitions anchored between the abutting edges of the slats 12 like as is illustrated in Figure 8 and also in Figure 3.

The bottom D is formed of sheet metal stamped to provide the double recesses 26 and 27. The recess 26 is of a nature and size to receive the base of the bottle C, while the recess 27 is of a size to receive the bead of the neck of the bottle C. In this manner I provide a bottom which will hold the bottles C more firmly therein, either in upright position or inverted as illustrated in the drawings. The bottom D is formed with drain openings 28 having depending annular flanges 29. The opening 28 is positioned co-axial with the formation of the recesses 26 and 27, thereby providing a uniform structure to the bottom and holding the bottles in a manner so that they can be drained out easily when they are inverted as illustrated in dotted outline in the drawings.

The bottom D may be anchored in the manner described for holding the side edges such as 19 of the partition B and in the preferred form of anchoring the edges of the bottom D the barb structure like 25 is used so that the edges of the bottom D are firmly anchored between the wooden slats 12 which make up the side and end walls of the crate A.

To further reinforce the crate A, I provide rivet stay-bolts 30 which are formed with shoulder 10 flanges 31 and conical riveting ends 32. These stay-bolts project from the upper partition to the bottom D and between the partitions B I provide tubular members such as 33 which act as spacers between the partitions and between the partition and the bottom D. When the rivet bolts 30 are placed in position as illustrated in Figures 3 and 4 with the spacer tubes 33 in place, the conical end 32 of the rivet is spun down to rivet the end of the bolt or rod 30 and provide a head portion 34 thereon which rigidly connects the rod or stay-bolt in operative position and forms a tight joint between the connecting parts. This formation of the riveting stay-bolt or rod is important also the anchoring of the same because it forms a water-tight joint and thus prevents moisture from acting readily to loosen the bolts at the connecting joint with the upper partition B and the bottom D.

By the forming of the crate A with the wooden side slats 12 and the simple stamped out partitions and bottom portions which are anchored to the side walls in the manner set forth, I provide a very desirable form of bottle crate which is particularly adapted for milk bottles and which is strong and durable. The stamped out construction of the partitions and bottom in a single piece provides an economy in construction, not only in the making of the crates A, but in the assembly thereof so that these crates may be produced with more economy and yet they are reinforced to provide a long wearing crate which will stand a considerable abuse and wear in the handling of the same.

In accordance with the patent statutes I have endeavored to set forth the best embodiment of my crate construction and the peculiar form of assembly which accomplishes certain desirable results in an economical manner, however, the same should be interpreted within the scope of the following claims.

I claim:

1. A bottle crate having partition members formed from sheet metal, bottle openings formed in said partition members with depending flanges about said openings, a bottom member formed from sheet metal, means for anchoring the edges of said partitions and said bottom in the side wall of the crate, and rivet staybolts extending between said partitions and bottom intermediate the sides thereof.

2. A bottle crate including, opposed pairs of side walls, partition means formed from sheet material, edges formed on said partition means for anchoring the same to the side walls, bottle openings formed in said partition means, a bottom member formed of sheet material, means formed on the edges for anchoring said bottom member to said side walls, and spaced brace rivet rods between opposed side walls and spaced therefrom extending from said partition means to said bottom member and riveted to said partition means and bottom member.

3. A bottle crate including, a partition member, side walls, and means for anchoring said

partition member to said walls including a spacing member adapted to bear against said wall and properly position said partition within said side walls.

5. 4. A bottle crate including, side walls built up of a series of superimposed slats, a partition member extendable between two adjacent slats, and a spacing member on said partition member engageable against said wall to hold said partition member in proper spaced relation.

10. 5. A bottle crate including, side walls, a par-

tition member extending into said side walls, and means for anchoring said partition member to said side walls including a spacing member on said partition member to hold said partition member in proper spaced relation.

6. A bottle crate including, side walls, a partition member extending into said side walls, and spacing means on said partition spaced from the edges thereof to hold said partition member in proper spaced relation.

LLOYD HALE.
